UNITED STATES PATENT OFFICE.

DAVID GOLDSMITH, OF NEWARK, NEW JERSEY.

GARMENT HANGER.

Application filed November 5, 1920. Serial No. 421,634.

To all whom it may concern:

Be it known that I, DAVID GOLDSMITH, a citizen of the United States, and a resident of Newark, in the county of Essex and State 5 of New Jersey, have invented new and useful Improvements in Garment Hangers, of which the following is a specification.

This invention relates to garment hangers adapted to receive and support long garments such as ladies' dresses, coats and the like, in a short compartment, such as a wardrobe trunk, the hanger comprising arms to receive the shoulders of the garment and a head which supports the hanger 10 on hooks, tracks or the like in a vertical plane with the garment inverted and the lower portions thereof draped or hung over the head of the hanger.

The objects of the invention are to provide an improved garment hanger of the character described constructed of wire and which is at the same time strong and durable; to provide such a hanger comprising a single length of wire doubled upon itself 25 and bent to form a supporting head and garment receiving arms; to provide such a hanger comprising an endless main frame constructed of wire and a second frame within the main frame to reinforce the hanger and provide a rigid and strong construction; to provide a garment hanger of this character having a main frame constructed of a single piece of wire bent to form a supporting head, body portion and 30 garment supporting arms, and having a second frame formed of a single length of wire arranged within the main frame to reinforce the same and rigidly connect the head and garment receiving arms to prevent 35 the head and garment receiving arms from bending or collapsing under the weight of the garment; and to obtain other results and advantages as may be brought out by the following description.

45 Referring to the accompanying drawings, in which like numerals of reference indicate the same parts throughout the several views,

Figure 1 is a front elevation of a garment hanger constructed in accordance with my 50 invention;

Figure 2 is a side elevation thereof, and

Figure 3 is a vertical sectional view taken on the line 3—3 of Fig. 1.

In the specific embodiment of the invention illustrated, the reference character A

designates a single piece of suitably heavy wire which is bent at two intermediate points in its length, as at 1, to form a portion 2, the wire being then returned parallel to the said portion 2 thereof as at 3 and extending to within a short distance of the center of the said portion 2 to form a head or support for the hanger, said wire being then bent at substantially right angles to said returned portions 3 to form spaced and parallel portions 4 comprising the body of the hanger, the wire being then curved outwardly in opposite directions from said body and inwardly toward the head of the hanger as at 5 and returned upon itself at 6 to form oppositely extending garment shoulder receiving arms projecting laterally upon opposite sides of the body 4 of the hanger and connected by the portion 7, the extremities of the wire being joined together in any suitable manner as by soldering or brazing to form an endless main frame. The portions 2 and 3 of the frame forming the head or support of the hanger are crimped adjacent their outer ends as at 8 to fit over supporting hooks or tracks such as are ordinarily used in clothes compartments, wardrobe trunks and the like to support the hanger in a vertical plane. The hanger is thus substantially T-shaped, and the head thereof, the garment shoulder receiving arms, and the body 4 are simply and inexpensively formed by doubling the wire upon itself and suitably bending it.

To reinforce the main frame of the hanger and rigidly connect the head thereof and the garment receiving arms to prevent bending or collapsing of the hanger under the weight of the garment, I provide a second frame within the main frame and formed of a single length of wire B doubled upon itself. The frame B is substantially I-shaped in construction and has an enlarged looped end 9 which is connected between the portions 2 and 3 of the head of the hanger, and a body comprised of the spaced and parallel portions 10 which are rigidly connected to the inner sides of the portions 4 of the body of the main frame, the said portions 10 terminating at their other ends in an enlarged head 11 connected between the outwardly curved portions 5 of the main frame and the portions 7 thereof connecting the garment receiving arms.

To apply a garment to the hanger, the

hanger is held in a substantially vertical position with the garment receiving arms uppermost and in a substantially horizontal position, the shoulders of the garment being 5 slipped over the garment receiving arms, after which the hanger is inverted so as to drape the lower portions of the garment over the head of the hanger. The hanger is then placed upon the supporting hooks or tracks 10 in the compartment in a vertical plane, the crimped portions 8 of the head of the hanger receiving the tracks or hooks.

With this construction it will be seen that a two-point suspension garment hanger can 15 be easily and inexpensively formed of wire and at the same time withstand the strains to which such hangers are usually subjected. The greatest amount of strain is placed upon the head of the hanger and the 20 head is reenforced by the frame B having the enlarged end 9 thereof connected between the portions 2 and 3 of the head. It will also be noted that the enlarged ends 9 and 11 of the frame 13 are directly connected 25 between the head of the main frame of the hanger and the garment receiving arms so as to prevent bending or collapsing of the hanger under the weight of the garment,

the portions 10 of the frame B serving to increase the rigidity of the hanger. 30

While I have illustrated and described only one possible embodiment of my invention it will be obvious that many detail modifications and changes can be made in the construction of the garment hanger by those skilled in the art without departing from the spirit or scope of the invention, and I do not desire to be limited in the construction and use of my invention except as required by the following claim when construed in 35 the light of the prior art.

Having thus described the invention, what I claim is:

A garment hanger comprising an endless main frame formed of a single piece of wire 45 doubled upon itself to form a body comprising a pair of spaced and parallel portions, said wire at the ends of said body extending outwardly in opposite directions and returning inwardly upon itself to form respectively a supporting head and garment supporting arms, and a second endless wire frame within said main frame and rigidly connected to said head, body and garment receiving arms to reinforce the hanger. 50

DAVID GOLDSMITH.
